(57) **CLAIM**

The ornamental design for a footwear, as shown and described.

DESCRIPTION

FIG. 1 is a bottom perspective view of a footwear, showing my new design;

FIG. 2 is a bottom plan view thereof;

FIG. 3 is a front elevational view thereof;

FIG. 4 is a rear elevational view thereof;

FIG. 5 is a left-side elevational view thereof;

FIG. 6 is a right-side elevational view thereof; and,

FIG. 7 is an enlarged perspective view of the area labeled 7 in FIG. 1.

The dot-dash lines represent the boundaries of the design as well as the boundaries of the area of enlargement seen in FIG. 7. The dot-dash lines themselves form no part of the claimed design. The remaining broken lines depict portions of the footwear that form no part of the claimed design.
